UNITED STATES PATENT OFFICE.

EDWIN E. SLICK, OF WESTMONT BOROUGH, PENNSYLVANIA.

INGOT-MOLD.

1,207,645.

Specification of Letters Patent.

Patented Dec. 5, 1916.

Application filed May 10, 1916. Serial No. 96,473.

To all whom it may concern:

Be it known that I, EDWIN E. SLICK, a citizen of the United States, residing in Westmont Borough, in the county of Cambria and State of Pennsylvania, (whose post-office address is Johnstown, Pennsylvania,) have invented certain new and useful Improvements in Ingot-Molds; and I do hereby declare the following to be a full, clear, and exact description of the invention, such as will enable others skilled in the art to which it appertains to make and use the same.

My invention relates to an ingot mold with special reference to the construction of the upper removable portion thereof, which is provided with a refractory non-conducting lining, adapted to maintain the metal liquid therein and to concentrate the piping cavity 15 in the upper portion so that the lower part or the body of the ingot itself may be solid and free from imperfections.

The mold itself is preferably metallic, although it may be made of other material, or 25 may comprise a flask lined with sand, loam, bricks or other refractories. My invention, however, is particularly applicable for use with metal molds, and I will therefore describe it in connection with such.

30 The sinkhead portion or upper part of my mold comprises generally a metallic casing, open top and bottom, of rectangular, octagonal or other form, as desired, preferably tapering upwardly, that is, with its smaller end upward, so that it may be readily withdrawn from the metal which is 35 cast therein. I may make this taper more or less and prefer to make it comparatively small, so as to maintain the upper portion 40 of the sinkhead as large as possible, thereby forming a considerable body of metal in which the shrinkage cavity will form entirely therein in such a way that it will not communicate with the body of the ingot.

45 The side of the metallic casing is preferably made in one piece and provided with lifting lugs, and has its bottom or lower end provided with a plate having a large central opening therein, which plate may 50 be adapted to rest on the upper edges of the metal ingot mold. Refractory materials, such as bricks of general prismatic form are introduced into this casing from its lower and larger end, and these bricks 55 are slightly tapered on their edges to accom-

modate themselves to the tapered conformation of the casing, so that they cannot be withdrawn from the upper and smaller portion of the casing. The closing plate is then placed on the lower end of the casing, with 60 parts of its surfaces adapted to contact with the lower ends of the bricks or lining to hold them in place and prevent them from slipping downwardly. The closing plate may also be provided with downward projections adapted to fit within the opening in the metallic mold, thereby locating it in 65 position and sealing the joint between the top and the mold, thereby preventing the formation of laterally projecting fins, which 70 would make irregularities on the ingot or interfere with the separation of the top from the ingot, or these projections may be omitted if desired.

75 By means of this construction, I am enabled to provide a top or sinkhead portion having a non-conducting lining of refractory materials or bricks of substantially uniform thickness throughout, thereby conducting to economy of materials, and this lining 80 is easily retained in place by the lower closing plate, while held in place by the slight taper of the inclosing flask or casing.

85 After my sinkhead top is placed on top of a mold in position for operation, the mold is filled with molten steel or other metal, also filling the sinkhead top portion, and by reason of the large contents of the sinkhead portion and the fact that it is provided with a refractory and non-conducting 90 lining, the heat is not dissipated therefrom, so that the metal therein remains fluid for a considerable time, allowing the shrinkage cavity to form therein, as the excess metal from the sinkhead top feeds downwardly 95 into the body of the ingot, causing the body portion of the ingot to become solid.

Having thus given a general description of my invention, I will now in order to make the matter more clear refer to the accompanying two sheets of drawings forming part of this specification and in which like characters refer to like parts.

Figure 1 is a vertical sectional elevation through the top of a metal ingot mold with 105 my improved non-conducting top thereon of generally rectangular section, this view being taken on the line I—I of Fig. 2; Fig. 2 is a top plan view of the aforesaid ingot mold top; Fig. 3 is a top plan view of the 110

retaining plate; Figs. 4 and 5 illustrate the side and end lining bricks. Fig. 6 illustrates in top plan a modified form of ingot mold and top of octagonal shape; Fig. 7 is a vertical sectional elevation through the top of the metal ingot mold and non-conducting top taken on the line VII—VII of Fig. 6; and Fig. 8 illustrates in plan an octagonal non-conducting ingot mold top seated on top of a substantially square ingot mold.

Referring first to the characters of reference on Figs. 1 to 5 of the drawings, 1 represents the upper portion of an ingot mold of substantially rectangular cross section, 2 are the lifting lugs of the same, 3 is the upper portion of the ingot contained therein, 4 is the outer casing of the sinkhead top portion, 5 are the lifting lugs thereof, 6 are ears or projections extending, 20 as illustrated, from the lower corners of the casing, 7 are holes or perforations formed in said ears, 8 is the retaining plate adapted to hold the refractory lining 13 and 14, composed of bricks, or other material, in 25 place from slipping downwardly when the ingot top is in position, 9 is a projection or flange extending downwardly into the ingot mold from the retaining plate, 10 are ears or projections formed on the corners of the 30 retaining plate corresponding to the projections 6 of the casing, these ears being provided with perforations or holes 11, adapted to register with the perforations 7 in the ears 6 of the casing 4, 12 are key bolts 35 adapted to be inserted through the openings aforesaid and hold the retaining plate in position against the casing 4, thereby retaining the lining 13 and 14 in position therein, 15 represents the sinkhead portion 40 of the ingot, 16 is the shrinkage cavity therein, 17 are the keys for the bolts adapted to secure the retaining plate 8 to the casing 4.

Referring now to Figs. 6, 7 and 8:— 45 18 represents a substantially octagonal ingot mold, 19 the lifting lugs thereof, 20 represents a substantially rectangular ingot mold, provided with lifting lugs 21, the ingot in the octagonal mold is indicated as 22, while 50 23 is the sinkhead portion of said ingot and 24 is the shrinkage cavity therein. The outer casing on the octagonal ingot mold is indicated as 25, provided with lifting lugs 26 and projecting ears 27, and with a retaining plate 28, adapted to conform generally to the shape of the mold. The downwardly extending flange on the retaining plate 28 is indicated as 29, the retaining plate being secured to the casing 25 by 55 means of the key-bolts 30 and the keys 31 in a manner similar to that further illustrated in Figs. 1 and 2. The refractory material or bricks lining the octagonal ingot mold top are indicated as 32, these being 60 preferably all of the same size and form

and of substantially uniform thickness from top to bottom, in order to economize material.

I have found that it is possible to use an ingot mold top of this kind many times, as 70 on account of its construction and slight upward taper, it can be withdrawn from the sinkhead and replaced on another mold ready for further use, so that the cost of this construction per ton of ingots is very 75 slight, as compared with the cost of other forms which can only be used once. The initial cost of non-conducting refractories for a top of this kind is also small, as the thickness thereof may be made uniform and 80 of the minimum amount to produce the effects desired, and this is not true of tops which are lined with bricks or other material of tapering or varying thicknesses, as the latter are made of varying thickness to 85 provide the required taper in the sinkhead and necessarily so to permit them to be introduced into the casing from the top.

One of the particular features of my invention resides in the use of a casing having a lining composed of bricks of substantially uniform thickness, retained from displacement upwardly by the slight taper of the flask and from dropping downwardly by a retaining plate mounted on the bottom 95 of the flask, which retaining plate may or may not be attached to the flask as desired.

Although I have shown and described my improvements in considerable detail, I do not wish to be limited to the exact and specific details shown and described, but may use such substitutions, modifications or equivalents thereof, as are embraced within the scope of my invention, or as pointed out in the claims.

Having thus described my invention what I claim and desire to secure by Letters Patent is:—

1. A mold top comprising a removable casing, a removable retaining plate mounted below and projecting inwardly from said casing, a refractory lining within said casing supported by the retaining plate aforesaid.

2. A mold top comprising a casing open top and bottom, a removable retaining plate mounted below and projecting inwardly from said casing, and a non-conducting lining composed of bricks of uniform thickness, supported by the retaining plate.

3. A mold top comprising a casing open top and bottom, a retaining plate mounted below and projecting inwardly from said casing and adapted to project downwardly into the mold, and a non-conducting lining composed of bricks of uniform thickness, supported by the retaining plate.

4. A mold top comprising a casing larger at its lower end, a removable retaining plate mounted below said casing and projecting

- inwardly thereof and supporting a refractory lining mounted within said casing.
5. A mold top comprising a casing, a retaining plate mounted below said casing and projecting inwardly thereof, a plurality of non-conducting bricks of substantially uniform thickness mounted within said casing and supported by the retaining plate, said retaining plate being provided with a flange or projection adapted to extend within the upper portion of the ingot mold.
6. A mold top comprising a casing larger at its lower end, a removable retaining plate mounted adjacent to the lower end of said casing and projecting inwardly thereof, means for securing said plate to said cas-

ing, and a plurality of bricks of refractory material of substantially uniform thickness mounted within said casing and supported by said retaining plate.

7. A mold top comprising a casing larger at its lower end, a removable retaining plate mounted against the lower end of said casing and adapted to project inwardly and downwardly thereof, means for securing said plate to said casing, and a plurality of portions of refractory material of substantially uniform thickness mounted within said casing and supported by said retaining plate.

EDWIN E. SLICK.
